UNITED STATES PATENT OFFICE.

CHARLES F. ROCKSTROH, OF NEW YORK, N. Y., ASSIGNOR TO ROCKSTROH-MANUFACTURING COMPANY, OF ORANGE, NEW JERSEY, A CORPORATION OF NEW JERSEY.

PRINTING-PLATE HOLDER.

No. 870,994.

Specification of Letters Patent.

Patented Nov. 12, 1907.

Application filed December 8, 1905. Serial No. 290,873.

To all whom it may concern:

Be it known that I, CHARLES F. ROCKSTROH, a citizen of the United States, residing at Richmond Hills, in the county of Queens, city and State of New York, 5 have invented an Improvement in Printing-Plate Holders, of which the following is a specification.

My invention relates to improvements in the devices employed for securing printing-plates to the slotted bed or foundation supporting the same in electrotype, 10 stereotype and other printing processes, and the same is an improvement upon the clamping device shown and described in Letters Patent granted to me January 26, 1904, No. 750,395. In this patent the tumbler or slot engaging devices are freely movable upon the revolvable screw stem on the printing-plate holder, the same usually moving according to the direction of movement of the screw. It is therefore necessary to make sure that said devices are in engagement with the walls of the slots.

20 The device of my present invention comprises a spring actuated member adapted to automatically engage the wall or walls of the slot of the grooved printing-plate foundation. This spring actuated device or member is preferably in the form of a spring actuated tumbler 25 adapted to come into engaging position at once when the printing-plate holder is placed down in a slotted groove of the printing-plate bed or foundation so as to prevent accidental vertical displacement of the register hook or printing-plate holder.

30 I prefer to provide each groove or slot with undercut shouldered side walls for engagement by said spring actuated device; the details of the structure are hereinafter more particularly described.

In the drawing Figure 1 is a plan representing a bed 35 or printing-plate foundation support with a printing-plate in position secured thereto by clamp devices. Fig. 2 is a side elevation representing a clamp device according to my invention. Fig. 3 is an elevation at the right hand end of the parts shown in Fig. 2, also 40 showing said parts in position in the slotted bed or foundation. Fig. 4 is an elevation of the parts shown in Fig. 2 at the right hand end, and Fig. 5 is a plan of the parts shown in Fig. 2.

The bed or plate support *a* of integral formation is 45 provided with series of slots 2 or grooves running parallel to one another and another series of slots or grooves 3 at right angles to the series 2.

Between the slots of the respective series there remain intervening squares *a*¹ and while each slot is 12 50 points or 1 pica wide, each intervening square is 36 points or 3 pica in either direction according to the well known form of type measurement.

By reference to Fig. 3 it will be apparent that these slots are of the same width at the top and at the bottom, 55 and that at an appreciable distance below the top sur-

face of the plate support or slotted foundation the intervening squares are undercut and shouldered to broaden the slots or grooves, the said slots or grooves therefore being formed with undercut shouldered portions and with side walls 4, 5, that converge toward the base of 60 the slots.

In Fig. 1 is shown an application of my invention in which an electrotype, stereotype or other printing-plate *b* is held in position by my improved clamp devices which may be those shown in the aforesaid Letters Patent 750,395 or those of the present application. These clamp devices are to be dropped, or in other words, passed freely down into the slots or grooves of the bed or foundation support and when they are to be removed they are raised bodily vertically out of the 65 slots or grooves, and while my improved clamp device is applicable in connection with a bed or foundation support for securing thereto electrotype, stereotype or other printing-plates, it is especially adapted for use where there are narrow margins, or in other words, 70 where adjacent edges of two printing-plates come comparatively close together. The essential feature of the invention being the spring actuated character of the clamp whereby the device preventing accidental displacement takes up its position automatically the moment that the clamp device is placed down in the slot or groove of the bed engaging the shouldered or undercut walls of the same.

The clamp device essentially comprises an elongated narrow body *c* of a width adapted to pass freely down 75 into a slot or groove of a bed or foundation support.

In height the body agrees substantially with the depth of the slots or grooves of the bed, and the same is elongated to a desired or predetermined extent; said body being provided with a jaw *c*¹ formed on the upper 80 surface and placed transversely to the body so that when in use it extends from the upper surface of the bed, and the same is undercut on its advancing edge so as to take a bearing over the inclined edge of the printing-plate. This body is longitudinally apertured 85 and interiorly threaded so as to receive a revolvable screw stem *d* adapted by its rotation to move the said body longitudinally along in a groove or slot in either direction.

A pinion *e* is secured to one end of the revolvable 100 screw stem *d* and adjacent to and outside of said pinion is a thrust-plate *f* having on its outer face a guide block *g* agreeing substantially in width with the width of the slot or groove.

The thrust-plate in one of the slots of the bed extends across a slot running in the opposite direction and bears upon the walls of the slot at right angles to the slot occupied by the body of the clamp device at the same time said thrust-plate bears against the faces of the two intervening squares *a*¹; the pinion being re- 105 110

ceived in the same slot as the thrust-plate and the guide block passes down between opposite faces of two squares fitting in the same groove as is occupied by the revolute screw stem and the body of the clamp device.

5. A rack such as is shown in my before mentioned patent may be employed to turn or revolve the pinion *e* and with it the screw stem *d*, for by these devices the body of the clamp device must be moved along to the desired position in the groove, the thrust plate compelling this movement.

As a means of securing the clamp device to the bed or slotted foundation and in the slots or grooves thereof, and prevent the accidental removal of the same, I employ a spring actuated member.

15. In Figs. 2 to 5 inclusive *h* represents a tumbler apertured and interiorly threaded to receive the revolute screw stem *d*. A part of this tumbler fits up closely against the end of the elongated body and a part of the tumbler is prolonged to extend over a part of the elongated body that is cut away; this is shown essentially in Fig. 2. The lower edge of this tumbler is provided by preference with the recess *h'* and the lower portion of the elongated body *c* is provided with an aperture 6; the spring *i* passing through this aperture 6 and at its 20 left hand end (Fig. 2) through a hole in the body where it is secured, the aperture 6 being very much larger than the spring wire so as to permit the free movement of the same. The fastening of said wire being at 7 in the body *c*.

25. The free end of the spring *i* bears in the recess *h'* of the tumbler and performs the function of bearing the tumbler toward one side. See Figs. 3 and 5.

The normal position in which this spring *i* holds the tumbler *h* is substantially shown in Fig. 3, and the 30 function of this spring is to cause this tumbler to bear to one side and from this position in order to pass the clamp device down into a slot of the bed or foundation, this tumbler must be turned so that its sides are vertical and substantially in line with the sides of the 35 elongated body *c*.

40. After the parts pass down into the slot of the bed or foundation, and the tumbler passes below the shouldered portion of the slot or groove, the spring turns the tumbler into an undercut part of the slot or groove so that the upper end of the tumbler bears beneath the shouldered portion, while one side of the tumbler lies substantially parallel with one converging wall of the 45 slot so as to hold the clamp device down in the slot in position against any force that may be exerted in 50 clamping the printing-plate to the bed, and which would tend to cause accidental displacement or lifting 55 of the clamp device.

To remove the clamp device from the slot or groove of the bed or foundation, it is only necessary to bring 55 the tumbler *h* into a vertical position by any suitable instrumentality and then bodily raise the device out of the groove.

I claim as my invention:

1. The combination with an integrally formed plate 60 foundation having series of grooves thereon provided with an undercut shouldered side wall, of a register hook having its base in one of said grooves, said register hook being provided with means for longitudinal adjustment and a spring actuated tumbler for engaging under the shoulder 65 of said side wall for retaining the hook within the groove.

2. In combination with an integrally formed supporting bed for printing plates, having grooves with undercut and

shouldered sides and walls downwardly extending from the undercut portions, a clamp device for engaging and holding printing plates to said bed having a spring actuated 70 tumbler adapted to come under the shouldered portions of the said groove.

3. In combination with an integrally formed supporting bed for printing plates having grooves and undercut and shouldered sides and walls downwardly extending from the 75 undercut portions, a clamp device for engaging and holding printing plates to said bed, comprising an elongated body portion with a clamping jaw, a revolute screw stem, means for fixing the position of said screw stem in a transverse groove to that occupied by the elongated body for 80 moving said body lengthwise of said groove, and a spring actuated tumbler adapted to come under the shouldered portions of the said groove for retaining the clamp device within the groove.

4. In combination with an integrally formed supporting bed for printing plates having grooves and undercut and shouldered sides and walls downwardly extending from the undercut portions, a clamp device for engaging and holding printing plates to said bed, comprising an elongated body portion with a clamping jaw, a revolute screw stem, 90 means for fixing the position of said screw stem in a transverse groove to that occupied by the elongated body for moving said body lengthwise of said groove, and a spring actuated member apertured and interiorly threaded to receive said revolute screw stem by which it is carried, said 95 spring actuated member being adapted to come under the shouldered portions of said groove for retaining the clamp device in position.

5. A clamp mechanism for holding a printing plate to a 100 grooved bed or foundation, consisting of the clamp and a spring actuated tumbler device adapted to engage in a groove in the bed and thereby secure the clamp to the bed, substantially as specified.

6. A clamp device for holding a printing plate to a 105 grooved bed or foundation, said clamp device comprising a body portion longitudinally apertured and interiorly threaded and adapted to pass freely down into a slot or groove of the bed, and having a jaw formed on the upper surface and placed transversely to the body and undercut on its advancing edge so as to take a bearing over the inclined edge of a printing plate, a revolute screw stem passing through the screw threaded aperture in the body portion and adapted by its rotation to move the body longitudinally along in a groove or slot in the bed in either direction, and a spring actuated tumbler for retaining the 115 clamp device in the groove.

7. A clamp device for holding a printing plate to a 120 grooved bed or foundation, comprising a body portion longitudinally apertured and interiorly threaded and adapted to pass freely down into a slot or groove in the bed, and having a jaw on the upper surface placed transversely to the body, a revolute screw stem passing through the screw threaded aperture in the body portion and adapted by its rotation to move the body longitudinally along in a groove in the bed in either direction, and a spring actuated 125 member longitudinally apertured and interiorly threaded to receive the said revolute screw stem by which it is carried, said spring actuated member being adapted to retain the clamp device within a groove in the bed or foundation.

8. A clamp device for use in the grooves of a bed for 130 holding printing plates thereto, the same consisting of a body portion having a jaw, a means for moving the same lengthwise, a stop device against which such movement is effected, a pivoted tumbler for holding the clamp device to the bed and a spring acting thereon to move the tumbler 135 to one side into operative position.

9. A clamp device for use in the grooves of a bed for holding printing plates thereto, comprising a body portion having a jaw, a means for moving the same lengthwise, a stop device against which such movement is effected, a laterally swinging shoulder engaging member, and a separate spring acting thereon to operate said laterally swinging shoulder engaging member.

Signed by me this seventh day of December 1905.

CHAS. F. ROCKSTROH.
